UNITED STATES PATENT OFFICE.

EDWARD GEORGE HUMMELL, OF LANCASTER, NEW YORK.

IRONING-BOARD.

SPECIFICATION forming part of Letters Patent No. 619,573, dated February 14, 1899.

Application filed December 31, 1897. Serial No. 664,855. (No model.)

To all whom it may concern:

Be it known that I, EDWARD GEORGE HUMMELL, of Lancaster, in the county of Erie and State of New York, have invented a new and 5 Improved Ironing-Board, of which the following is a full, clear, and exact description.

The object of the invention is to provide a new and improved ironing-board which is simple and durable in construction, easily set up 10 against a table, chair, or other support, and arranged to permit of convenient folding for transportation, storing, or other purposes, the device being also serviceable as a shelf for supporting various articles.

15 The invention consists of novel features and parts and combinations of the same, as will be described hereinafter and pointed out in the claim.

Reference is to be had to the accompanying 20 drawings, forming a part of this specification, in which similar characters of reference indicate corresponding parts in all the figures.

Figure 1 is a perspective view of the improvement as extended. Fig. 2 is a sectional 25 side elevation of the improvement folded up. Fig. 3 is an enlarged plan view of the extension-brace. Fig. 4 is an enlarged sectional side elevation of part of the same on the line 4 4 of Fig. 3; and Fig. 5 is an inverted plan 30 view of a portion of the board, showing the spring-clamp.

The table A for the ironing-board or shelf is provided at one end and at the under side with a spring-clamp B, adapted to securely 35 hold this end of the table against a chair, ordinary table-top, or like support. On the under side of the table A and at a suitable distance from said clamp B is pivoted a leg C by means of hinges D, so that the leg can be 40 swung into an angular position relatively to the table A and in a forward direction from the support to securely hold the table A in a horizontal position for ironing purposes.

The leg C is connected with the forward 45 end of the table A by an extension-brace E, provided with a tube E', formed at one end with transverse trunnions E², engaging bearings F on the upper face of the leg C. In the tube E' is fitted to slide a rod E³, pivotally 50 connected at its forward end to a lug G, attached to the under side of the table A. The free end of the tube E' is formed with an extension E⁴ at a right angle to the tube and containing a locking-bolt H, adapted to engage teeth E⁵, formed on one side of the rod

E³, to hold the latter in an extended position relatively to the tube E' to bring the table A in the desired horizontal position relatively to the height of the table, chair, or other support connected with the table by the spring- 60 clamp B.

The bolt H is provided at the outer end of the extension E⁴ with a suitable knob H', adapted to be taken hold of by the operator for withdrawing the bolt H from the teeth E⁵ 65 to permit of sliding the rod E³ inwardly in the tube E'. The bolt H is prevented from turning by a pin I, held in the extension E⁴ and passing through an elongated slot H², formed in the bolt H, said slot also containing a coil-spring J, resting with one end on the pin I and with its other end against the bolt H, so as to press the same in engagement with the teeth E⁵.

On the upper face of the leg C is formed a 75 recess C', and a similar recess A' is formed on the under side of the table A to receive the several parts of the extension-brace E when the leg C is folded against the under side of the table A, as is plainly indicated in 80 Fig. 2, to permit of folding the several parts into as small a compass as possible for transportation, storing, or other purposes.

Now it will be seen that by the arrangement described the ironing-board A may be 85 readily set up at any desired height, according to the support against which one end of the table rests, the extension-brace permitting of giving the desired distance between the leg C and the table A to bring the latter 90 into proper position.

The device can be readily used as a bench or seat by adjusting it to a suitable support.

Having thus fully described my invention, I claim as new and desire to secure by Letters 95 Patent—

The combination of the table, the leg pivoted thereto, the extensible brace consisting of sliding sections connected respectively to the table and to the leg, one of said sections 100 being tubular and having its free end bent laterally, while the other section is toothed and passes into the tubular section, and a locking member fitted to slide in the lateral extension of the tubular section and to engage the toothed section of the brace.

EDWARD GEORGE HUMMELL.
